UNITED STATES PATENT OFFICE.

WILLIAM GERHARDT, OF HAZLETON, PENNSYLVANIA.

CLOTH-CUTTING MACHINE.

SPECIFICATION forming part of Letters Patent No. 666,513, dated January 22, 1901.

Application filed April 4, 1900. Serial No. 11,481. (No model.)

To all whom it may concern:

Be it known that I, WILLIAM GERHARDT, a citizen of the United States, and a resident of Hazleton, in the county of Luzerne and State 5 of Pennsylvania, have invented a new and Improved Cloth-Cutting Machine, of which the following is a full, clear, and exact description.

The purpose of this invention is to provide 10 an electrically-operated cloth-cutter, which may be freely moved over the cutting-table and effectively cut the cloth without necessitating the operator using one hand to press the cloth down and feed it into position, since 15 this frequently causes the operator to be seriously cut by the machine.

This specification is the disclosure of one form of the invention, while the claims define the actual scope thereof.

20 Reference is to be had to the accompanying drawings, forming a part of this specification, in which similar characters of reference indicate corresponding parts in all the views.

Figure 1 is a side elevation of the invention. Fig. 2 is a vertical section thereof. Fig. 3 is a plan view. Fig. 4 is a cross-section on the line 4 4 of Fig. 1. Fig. 5 is a cross-section on the line 5 5 of Fig. 1. Fig. 6 is a detail view of the contact device. Fig. 7 is a 30 section on the line 7 7 of Fig. 6, and Fig. 8 is a section on the line 8 8 of Fig. 1.

The machine is provided with a flat base 10, which has suitable knobs or the like 11 on its bottom, facilitating the sliding of the machine over the cutting-table. A hollow standard 12 is erected on the base 10 and carries at its upper portion an electric motor 14, which may be of any desired form. As shown best in Fig. 2, this motor comprises a tubular projection 15, on which a lamp 16 is carried. (See Fig. 1.) The conductors for the lamp are led through the tubular projection 15 and placed in connection with the circuit of the motor, as will be understood. The 45 electrical energy is led to the motor by a conductor-cord 17, which is fitted with a weight 18, having a sheave 19 therein, which runs on the cord to keep the cord at the proper tension. The cord is held fast to the motor 50 by means of a thumb-screw 20, carried by an arm 21 on the motor. By thus holding the

conductor-cord 17 fast the strain of the weight 18 and other influences will not affect the various connections on the motor. The cord 17 is carried on a number of sheaves 22, which 55 are sustained in cheek-rings 23. These rings are two in number and fastened rigidly together by the pins of the sheaves 22. The rings 23 are swiveled on a tubular connection 24, which is fast to a plate 25, that may be 60 attached to the ceiling or any other overhead support by means of screws and thimbles 26, as shown. Through this tubular connection 24 the conductor-cord 17 is led from a suitable switch 27, as shown in Fig. 1. The rings 65 23 being free to turn it will be seen that the operator may use the cutter in any desired position without interference from the electrical connections, and it will also be seen that the weight 18 will hold the conductor-cord 17 70 taut. I provide means for throwing the motor into and out of connection with the circuit, which means are shown in Figs. 1, 6, and 7. These means comprise an insulating-block 43, having two pins 44 therein, which 75 are in connection with the positive and negative poles of the motor. A second insulating-block 45 is provided and carries two pins 46, that are in connection with the wires of the conducting-cord 17. The block 43 has 80 conducting-sleeves 47 fitted therein and in electrical connection with the pins 44, and into these sleeves 47 the ends of the pins 46 may be projected, thus establishing the necessary connections. To work these connections, the block 45 may be moved out of the 85 position shown in Figs. 1 and 6, thus stopping the action of the motor. The motor, of course, may be provided with various other appliances for facilitating its operation, as will 90 be understood by persons skilled in the art.

Arranged in the standard 12 are two stub-shafts 28, which are located one above the other and carry, respectively, the circular knives 29. These knives are oppositely bevelled and work against each other, as shown, the knives overlapping, so as to form a shear cut between them. A cutting-plate 30 is also provided to work with the lower knife 29, such plate being fastened on the base 10 and 100 being slotted, so that the knife may be projected through it. It will therefore be seen

that the cutting capacity of the instrument extends from a point on top of the base 10 up to a point above the axis of the upper knife 29. The knives 29 are driven from a shaft 31, which is passed transversely through and mounted in the stub-shafts 28. The upper end of the shaft 31 is mounted in the box 32, which carries the armature-shaft of the motor. Within this box 32 is a bushing 33, into which the upper extremity of the shaft 31 projects, thereby locking the bushing in place and preventing it from longitudinal movement in the bearing. The armature-shaft is fitted with a bevel-gear 34, which meshes with a pinion 35 on the shaft 31. Each knife 29 is provided with a beveled gear 36, and these gears 36 are meshed with beveled pinions 37 on the shaft 31. The pinions 37 may be disposed in any position relative to the gears 36, so as to regulate the direction in which the knives are driven, and by varying the size of the gears employed the speed of the knives may also be regulated. As shown in Fig. 1, the knives are principally inclosed in the hollow standard 12, only their cutting edges at the front of the standard being exposed.

For the purpose of guiding the cloth and for pressing it down on the table in position to be properly cut I provide a pressure-arm 38, the front end of which is turned upward to form a shoe which may ride freely over the top of the cloth. The inner or rear portion of the arm 38 is fitted to slide in a sleeve 39, formed on the upper portion of the standard 12, such sleeve being provided with a set-screw 40 to hold the arm 38 rigidly in place. The inner end of the arm 38 is threaded, and on this portion of the arm works a thumb-nut 41, by the operation of which the arm 38 may be raised or lowered to suit the amount of cloth to be cut. The nut 41 is seated in a cavity formed in the upper portion of the standard 12 and is therefore incapable of all movement except a rotary movement, which is sufficient to advance or retract the arm, as will be understood. A handle 42, of any suitable form, is attached

to the rear of the apparatus to permit the manipulation thereof.

In using the invention the operator grasps 50 the handle 42 and moves the machine over the table, causing the base 10 to slide under the cloth and the arm 38 to bear down on top thereof to press the cloth together and facilitate the action of the knives. When the motor is started, the knives revolve rapidly in either direction desired and work throughout the whole of their exposed faces.

Having thus described my invention, I claim as new and desire to secure by Letters 60 Patent—

1. A cloth-cutting machine having a base with a framing erected thereon, a motor carried at the upper part of the framing, a circular knife mounted at the lower part of the 65 framing above the base and driven by the motor, a pressure-arm located above the knife and having a curved part carried in a curved guide in the framing and adjustably held therein, the pressure-arm extending forwardly 70 and downwardly and having its lower end curved upward to form a shoe adapted to ride over the cloth to be cut.

2. A cloth-cutting machine having a base, a framing erected thereon, a motor carried in 75 the upper part of the framing, two stub-shafts mounted on the framing below the motor and having transverse openings in their ends, a circular knife mounted on each stub-shaft, the knives having each a bevel-gear thereon, 80 a vertically-disposed rotary shaft geared with the motor and extending through the openings in the ends of the stub-shafts said openings forming bearings for the vertical shaft, and bevel-gears fastened to the vertical shaft 85 meshing respectively with the bevel-gears on the knives.

In testimony whereof I have signed my name to this specification in the presence of two subscribing witnesses.

WILLIAM GERHARDT.
